UNITED STATES PATENT OFFICE.

HERMAN TAPPAN, OF NEW YORK, N. Y.

DESIGN FOR A BOUQUET-HOLDER.

SPECIFICATION forming part of Design No. 17,023, dated December 14, 1886.

Application filed September 25, 1886. Serial No. 214,569. Term of patent 3½ years.

To all whom it may concern:

Be it known that I, HERMAN TAPPAN, a citizen of the United States, residing at New York, in the county and State of New York, have invented and produced a new and original Design for Bouquet-Holders, of which the following is a specification, reference being had to the accompanying drawing, in which the figure is a perspective view representing my new and original design.

The leading feature of my design consists of a boot resting on a base-plate. The boot A has the hollow shank B, and the heel C and part of the sole D rest on the base-plate E. The shank B has a checkered ground, F, ornamented by disks G in relief, and by a band, H, in front, partly ornamented with projections I. On the scalloped flap J of the shank B are represented buttons K in relief. The toe of the boot is ornamented by a tip, L.

I claim—

1. The design for a bouquet-holder herein shown and described, the same consisting of the boot A, having the shank B, ornamented with a checkered ground, F, the disks G, the band H, having the projections I, and the flap J, having the buttons K, as set forth.

2. The design for a bouquet-holder herein shown and described, the same consisting of the boot A, having the shank B, ornamented with a checkered ground, F, the disks G, and the band H, partly ornamented with projections I, the flap J, ornamented with the buttons K, the toe having the tip L, and the base-plate E, on which the said toe rests, as set forth.

HERMAN TAPPAN.
